UNITED STATES PATENT OFFICE

91,447

DESIGN FOR A LIQUID DISPENSER OR THE LIKE

George E. Wehrenberg, Chicago, Ill., assignor to Regalite, Inc., Chicago, Ill., a corporation of Illinois

Application February 2, 1933. Serial No. 47,085

Term of patent 3½ years

To all whom it may concern:

Be it known that I, GEORGE E. WEHRENBERG, a citizen of the United States, residing at Chicago, in the county of Cook and State of Illinois, have invented a new, original, and ornamental Design for Liquid Dispenser or the like, of which the following is a specification, reference being had to the accompanying drawing, forming part thereof.

Fig. 1 is a side elevation of a liquid dispenser showing my new design;

Fig. 2 is a front elevation thereof;

Fig. 3 is a plan, with the container removed to show features of the design that appear below the same, and

Fig. 4 is a rear elevation of the liquid dispenser showing the design.

I claim:

The ornamental design for a liquid dispenser or the like, substantially as shown.

GEO. E. WEHRENBERG.
